INVENTOR:
STEPHEN RYDER,
BY H. W. Beadle & Co.
ATTYS.

UNITED STATES PATENT OFFICE.

STEPHEN RYDER, OF NORTH ATTLEBOROUGH, MASSACHUSETTS, ASSIGNOR
OF ONE-HALF TO JOSEPH LEWIS BLAINE, OF SAME PLACE.

ELECTRICAL CONNECTOR.

SPECIFICATION forming part of Letters Patent No. 292,180, dated January 22, 1884.

Application filed November 2, 1883. (No model.)

To all whom it may concern:

Be it known that I, STEPHEN RYDER, of North Attleborough, county of Bristol, and State of Massachusetts, have invented new and 5 useful Improvements in Electrical Connectors; and I do hereby declare that the following is a full and exact description of the same, reference being had to the accompanying drawings, and to the letters of reference marked 10 thereon.

This invention relates to that class of electrical devices which are employed to connect the ends of different wires; and it consists in certain peculiarities of construction, fully described hereinafter, by means of which great simplicity is combined with perfect efficiency in obtaining the desired result.

In the drawings, Figure 1 represents a perspective view of my improved connector; Fig. 20 2, a top view of the button; Fig. 3, a plan view of the connector reversed; Fig. 4, a sectional view of the same; and Fig. 5, an enlarged view illustrating the relative position of the parts.

To enable others skilled in the art to make 25 my invention, I will proceed to describe fully the construction of the same.

A, Fig. 1, represents a block or base-piece of any proper material.

B represents a copper button having a central opening, as shown in Fig. 2, for the reception of a screw.

b, Figs. 3 and 4, represents a central portion of the button, which is depressed to form an annular flange, as shown.

b', Figs. 3 and 4, represents a peripheral portion, which is bent downward to form a rim or flange, as shown.

b² b², Fig. 4, represent semicircular openings in the rim, by means of which provision is 40 made for properly receiving and holding the wires.

b³ b³ represent teeth projecting from the edge of the rim at proper distances apart, which are adapted to sink into the block, as 45 shown in Figs. 1 and 4, for the purpose of fastening the connector securely in place.

C, Figs. 1, 3, and 5, represents the continuous wire, and c the auxiliary wire, which is to be connected therewith.

D represents the securing-screw. The position of the parts when the connector is completed is shown in Figs. 1, 3, and 5.

The continuous wire, it will be observed, having a proper portion of its length exposed, is in direct contact with the edge of the annular flange b of the copper button B, as shown in Figs. 3 and 5, the flange itself being firmly pressed upon it by the action of the securing-screw. The auxiliary wire, it will be observed, having a proper portion of its length exposed, is also in direct contact with the edge of this annular flange b, this flange also being firmly pressed upon it by the action of the securing-screw. The parts in this position are firmly held against disconnection. The button itself is firmly held by means of its teeth, which are embedded in the base-block, and by means also of the securing-screw. The wires are securely held by the pressure of the annular flange b, and by the clamping action of the 60 rim b'. By means of this construction the wires are brought together in such manner that the electrical connection is certain to be formed. The parts also are firmly secured in their proper relative positions. The connector, also, in view of the effectiveness of the 65 result obtained, is very simple.

Having thus fully described my invention, what I claim as new, and desire to secure by Letters Patent, is—

1. The copper button B, having the peripheral rim b, with openings for the wires and screw D in combination therewith, for moving it in a downward direction in such manner as to clamp the wires, as described.

2. The connector described, having the copper button with flange b, and rim b', having openings and teeth, in combination with a base-block and securing-screw, as described.

This specification signed and witnessed this 18th day of October, 1883.

STEPHEN RYDER.
